UNITED STATES PATENT OFFICE

151,801

DESIGN FOR A TOY ANIMAL FIGURE

Amy von Erdberg, Boston, Mass.

Application October 18, 1947, Serial No. 142,001

Term of patent 14 years

(Cl. D34—2)

To all whom it may concern:

Be it known that I, Amy von Erdberg, a citizen of the United States, residing at Boston, in the county of Suffolk and State of Massachusetts, have invented a new, original, and ornamental Design for a Toy Animal Figure, of which the following is a specification, reference being had to the accompanying, drawing, forming part thereof.

Fig. 1 is a front view of a toy animal figure, showing my new design;

Fig. 2 is a side view thereof looking to the left of Fig. 1; and

Fig. 3 is a left rear perspective view of the toy animal figure.

I claim:

The ornamental design for a toy animal figure, as shown.

AMY VON ERDBERG.
